PIE FRY BASKET

Steve Kroll, Schaumburg, Ill., assignor to Restaurant
Technology, Inc., Oak Brook, Ill.

Filed Oct. 15, 1973, Ser. No. 406,391

Term of patent 14 years

Int. Cl. D7—02

U.S. Cl. D7—95

FIG. 1

FIG. 2

FIG. 3

FIG. 7

FIG. 8

FIG. 1 is a top perspective view of a pie fry basket showing my new design;

FIG. 2 is a further top perspective view of the pie fry basket of FIG. 1 taken from the opposite side;

FIG. 3 is a side elevational view of the pie fry basket of FIG. 1;

FIG. 4 is an end view of the pie fry basket of FIG. 1 taken substantially along the line 4-4 of FIG. 3;

FIG. 5 is a sectional view of the pie fry basket of FIG. 1 taken substantially along the line 5-5 of FIG. 3;

FIG. 6 is a view of the pie fry basket taken substantially along the line 6-6 of FIG. 3;

FIG. 7 is a plan view of the pie fry basket of FIG. 1; and

FIG. 8 is a bottom view of the pie fry basket of FIG. 1.

I claim:

The ornamental design for a pie fry basket, substantially as shown.
